UNITED STATES PATENT OFFICE.

WILLIAM D. MYERS, OF HUMBOLDT, IOWA.

DEVICE FOR ADJUSTING FINGER-BARS.

SPECIFICATION forming part of Letters Patent No. 653,031, dated July 3, 1900.

Application filed March 9, 1900. Serial No. 7,985. (No model.)

To all whom it may concern:

Be it known that I, WILLIAM D. MYERS, a citizen of the United States, residing at Humboldt, in the county of Humboldt and State of Iowa, have invented a new and useful Device for Adjusting Finger-Bars of Mowers, of which the following is a specification.

In the operation of reapers and mowers the hinged finger-bars upon which cutter-bars are mounted frequently get out of alinement with the pitman, and the free rectilinear reciprocating motions of the cutter-bars are then impeded and the machines strained and damaged and the labor of the horses increased by such abnormal position of the finger-bar.

My object is to provide simple and efficient means for adjusting finger-bars as required to maintain them in perfect alinement with the pitmen; and my invention consists in the arrangement and combination of parts, as hereinafter set forth, pointed out in my claims, and illustrated in the accompanying drawings, in which—

Figure 1 is a perspective view of the heel end portion of a shoe to which a finger-bar is to be fixed. Fig. 2 is a perspective view of a pivot-bearing adapted to be adjustably connected with the vertical extension and pivot-bearing support on the heel end of the shoe. Fig. 3 is a top view of the shoe, showing my invention applied and a section of a finger-bar fixed to the shoe and the shoe hinged to a frame adapted for coupling the finger-bar to a reaper or mower as required for practical use. Fig. 4 is a modification showing the adjustable pivot-block mounted in one of the bifurcated end portions of the coupling-frame.

The letter A designates the shoe, and A² is an integral lug or support for a pivot-bearing. It has an angular recess B for the admission of a pivot-bearing and an opening C intersecting the recess for the reception of a lateral extension d of the pivot-bearing B². A mating lug and pivot-support A³ is integral with the central portion of the shoe, and by means of the two lugs A² and A³ the shoe A is hinged to the bifurcated extensions F and F² of the coupling-frame H, as shown in Fig. 3. The inner face of the block or pivot-bearing B² and the depressed face in the re-

cess B are ratchet-faced, and by means of slots J in the lug A² and clamping-screws extended through perforations in the block or pivot-bearing B² and said slots the pivot-bearing can be readily detachably and adjustably fixed in the recess B of the lug A². 55

K is the end portion of a finger-bar fixed to the shoe as required for supporting and carrying a cutter-bar. It extends in alinement with the groove m in the plate N, fixed to the finger-bar and shoe, as shown in Fig. 3. The groove m is a bearing for the pitman of a cutter designed to be mounted upon the finger-bar. 60 65

Dotted lines in Fig. 3 indicate how finger-bars will get out of alinement by use, and the advantages of my invention are obvious when it is observed I have provided simple and practical means for adjusting one of the pivot-bearings in the shoe, and thereby restoring a deflected finger-bar to its normal position in alinement with the pitman required for operating a reciprocating cutter-bar on the finger-bar. Such adjustment is readily accomplished by simply moving the adjustable block or bearing B² in the recess B of the lug A² on the shoe A. In place of putting an adjustable block or pivot-bearing in the lug of the shoe it may be fitted in one of the members of the bifurcated end F² of the frame H, as shown in Fig. 4. 70 75 80

Having thus described the construction, application, and function of my invention, its practical operation and utility will be readily understood by persons familiar with the art to which it pertains. 85

What I therefore claim as new, and desire to secure by Letters Patent therefor, is—

1. In a reaper and mower, a shoe having integral lugs for pivotally connecting it with a coupling-frame for hinging a finger-bar to the machine and one of the lugs on the shoe provided with an adjustable bearing for a pivotal bolt to operate in the manner set forth for the purposes stated. 90 95

2. The shoe A having lugs A² and A³, a recess B in one of the lugs an opening C and slots J intersecting the recess and a block or pivot-bearing B² having an extension d fitted in said recess and intersecting openings and clamping-screws extended through the pivot- 100

bearing and the slots in the lug on the shoe, as shown and described for the purposes stated.

3. In a reaper or mower the combination of a shoe having integral lugs or pivot-bearings, an adjustable block or bearing for a bolt or pivot fitted in a recess in one of said lugs, a finger-bar fixed to the shoe and a coupling-

frame having bifurcated ends to admit the lugs on the shoe, to operate in the manner set forth for the purposes stated.

WILLIAM D. MYERS.
